PROTECTOR

Roy McK. Mann, Burgettstown, Pa., assignor to
Ohio Valley Safety Apparel Company, Steubenville, Ohio, a corporation of Ohio

Application October 29, 1936, Serial No. 108,245

3 Claims. (Cl. 2—16)

This invention relates to improvements in protectors, and more particularly to improvements in arm protectors to be worn by industrial workers.

5 Many industrial workers handle heavy hot metallic articles, as, for example, sheets, having sharp edges from which the arms of the workers must be protected. At the same time any protective device should be comfortable, light in weight, 10 easily cleaned and of comparatively low cost of manufacture. I provide an arm protector which gives positive protection, is extremely resistant to ordinary wear and tear, and is very comfortable. It is light in weight and fits the arm of the 15 wearer perfectly because it is flexible and readily adjustable. The worker can easily fasten the protector to his arm or speedily remove it. In addition, it may be easily cleaned.

My protector preferably comprises a base of 20 soft flexible partially woolen material which surrounds the arm of the wearer, and a flexible protective covering which is removably attached to the base. This protective covering is preferably armored, as with metallic staples, to provide additional protection against sharp edges. Means 25 are also provided for securing the protector to the arm of a wearer.

It has heretofore been proposed to provide an arm protector of the general type above mentioned. Such a protector is disclosed in United States Patent No. 1,851,011. My protector is an improvement on the structure disclosed in said patent and obtains important advantages thereover. A base made of substantially pure wool 30 fibers is disclosed by the patent, whereas my base is of only partially woolen material. I have found that such a base is much less irritating to the skin of the wearer. In the arm protector of the patent the armored protective covering is permanently fastened to the base. I detachably fasten the cover to the base whereby the utility of the protector is greatly increased. Its cleaning is facilitated, as the base which requires frequent washing because of the accumulated dirt and 40 perspiration may be detached from the protective means for cleaning. Moreover, the relatively inexpensive base wears out much more rapidly than the protective covering with its metallic reinforcements. My arm protector may be kept 45 in serviceable condition for an extended period at little expense by replacing a worn out base by a new one, which is not possible with the prior device. When in use, the arm protector may temporarily become uncomfortable because 50 of sliding down the wearer's arm. If a workman

is handling metal sheets as they come off a mill, he will not have time to take the arm protector completely off his arm in order to smooth out some unevenness, but he can loosen one or more of the fasteners which secure the protective covering to the base and quickly make temporary adjustments. 5

Other advantages and details of construction of my invention will become apparent as the following description of a present preferred embodiment thereof proceeds.

In the accompanying drawing, I have shown a present preferred embodiment of the invention, in which

Figure 1 is a plan view of the base of an arm 15 protector;

Figure 2 is a plan view of the protective covering;

Figure 3 is a cross-sectional view to enlarged scale taken on the line III—III of Figure 2 and 20 showing the protective covering in place on the base, the protective covering being indicated separately before attachment to the base in chain lines; and

Figure 4 is a transverse cross-sectional view to 25 the same scale as Figure 3 taken on the line IV—IV of Figure 2, and showing the covering in place on the base.

Referring more particularly to the drawing, there is shown a base 5 of sufficient length to 30 encircle the wearer's arm and to slightly overlap. Because this base is in direct contact with the wearer's arm, it must be made of material having a soft texture. Any suitable material may be used, but I prefer to use heavy cloth which 35 is part wool and part cotton. This material not only has a soft surface but is flexible, comparatively light in weight and capable of absorbing a large amount of perspiration. I have found that cloth containing about 60% wool is especially 40 advantageous as causing the least irritation to the skin of the wearer. The edge of the base may be reinforced by stitching such as a blanket stitch 6 shown in Figure 1. Additional reinforcing stitching 7 may also be used. 45

One edge 8 of the base 5 is folded back on itself as shown in Figure 1, and held in place by the stitching 7. This edge is nearest the hand of the wearer and the double layer protects the wearer beyond the protective covering, later to 50 be described, while affording greater freedom of movement. The edge 8 is not folded back on itself throughout the entire length of the edge of the base 5, but extends only the length of the protective covering in order that the balance of 55

the base 5 which overlaps when in use will not be unnecessarily bulky.

The protective covering is designated generally by reference numeral 9. It is made of material heavier than the material of the base, but is still flexible. Leather is especially suitable. To prevent the protective covering from being cut by metal articles having sharp edges, such as sheets, its surface is preferably covered with metallic staples 10. These staples are so arranged that the surface of the protective covering 9 is adequately armored without any substantial decrease in flexibility.

The protective covering 9 carries spring eyelets 15 or snappers 11 which cooperate with studs 12 mounted on the base 5 as shown in Figure 1. These spring eyelets 11 and studs 12 provide an effective means for detachably securing the protective covering to the base 5.

Hollow eyelets 13 are located at intervals in the protective covering and provide ventilation for the base 5 and allow moisture absorbed by the base to evaporate. The eyelets 13 extend only through the protective covering 9 and not through the base 5. The eyelets are preferably disposed opposite unperforated portions of the base. Thus, the eyelets do not come into contact with the skin of the wearer whereby they might cause irritation. Also the positioning of the eyelets opposite unperforated portions of the base provides for most effective evaporation of perspiration absorbed by the base from the skin of the wearer.

To secure the protector to the arm of the wearer, I provide straps 14, preferably made of leather, carrying buckles 15 and attached to the protective covering 9 by rivets 16. The buckles 15 are adjustable along the straps 14 and carry spring eyelets or snappers 17. When the protector is disposed about the wearer's arm the straps 14 extend to the end of the protective covering 9 opposite the end to which they are attached and the buckles 15 are adjusted so that the snappers 17 cooperate with studs 18 mounted on the protective covering 9.

The straps 14 are preferably attached by the rivets 16 only to the protective covering 9 and not to the base 5. This further facilitates replacement of the base as the protective covering will ordinarily outlast several bases and when changing bases it is not necessary to do any-

thing with the straps and buckles which are attached only to the protective covering.

Thus my protector gives positive protection to the wearer without causing irritation, and is light in weight, flexible, readily adjustable, and provides for effective evaporation of perspiration. It can be easily cleaned, and can be manufactured and kept in repair at low cost.

While I have shown and described a present preferred embodiment of my invention, it is to be distinctly understood that the same is not limited thereto but may be otherwise variously embodied within the scope of the following claims.

I claim:

1. An arm protector comprising a flexible base of sufficient size to encircle a wearer's arm, flexible protective means having a plurality of small metallic particles spaced about the surface thereof, said protective means covering a portion of said base and being detachably secured thereto, said protective means having hollow eyelets extending only therethrough, and straps attached only to said protective means for securing the protector to the wearer, said straps having adjustable spring eyelet fasteners for attachment to said protective means.

2. An arm protector comprising a cloth base of sufficient size to encircle a wearer's arm, leather protective means having a plurality of metallic particles spaced about the surface thereof, said protective means covering a portion of said base and being detachably secured thereto, hollow eyelets extending only through said protective means for ventilation of said cloth base, straps attached only to said protective means at one end thereof for securing the protector to the wearer, said straps having detachable spring eyelet fasteners for engagement with studs fastened on the opposite end of said protective means.

3. An arm protector comprising a flexible base of sufficient size to encircle a wearer's arm, flexible protective means having a plurality of small metallic particles spaced about the surface thereof, said protective means covering a portion of said base and being detachably secured thereto, said protective means having hollow eyelets extending only therethrough, and straps attached only to said protective means for securing the protector to the wearer.

ROY MCK. MANN.
